DESIGN FOR A LIGHTER

Abner Kolberg, Mount Vernon, and Julius Kohn,
New York, N. Y., assignors to Pioneer Watch
Case Co., Inc., Mount Vernon, N. Y., a corporation of New York

Application December 28, 1944, Serial No. 117,126

Term of patent 14 years

(Cl. D48—27)

To all whom it may concern:

Be it known that we, Abner Kolberg and Julius Kohn, both citizens of the United States, residing in Mount Vernon, Westchester county, and State of New York, and New York city, Bronx county, and State of New York, respectively, have invented a new, original, and ornamental Design for a Lighter, of which the following is a specification, reference being had to the accompanying drawing, forming part thereof.

design with a portion thereof in adjusted position.

We claim:

The ornamental design for a lighter, substantially as shown.

ABNER KOLBERG.
JULIUS KOHN.
